UNITED STATES PATENT OFFICE.

EUGEN REISZ, OF ZEHLENDORF-MITTE, GERMANY.

ELECTRICAL CIRCUIT FOR THERMIONIC DISCHARGE DEVICES.

Application filed May 25, 1921. Serial No. 472,618.

To all whom it may concern:

Be it known that I, EUGEN REISZ, a citizen of Hungary, and a resident of Zehlendorf-Mitte, Germany, have invented a new and Improved Electrical Circuit for Thermionic Discharge Devices, (for which I have filed applications in Germany April 8, 1919, and Oct. 25, 1919), of which the following is a full, clear, and exact description.

10 This invention relates to electrical circuits for use in connection with thermionic discharge devices, and has for an object the provision of a circuit arrangement whereby the degree of amplification of these devices is increased.

Another object resides in the provision of means whereby the use of inductive windings in a circuit for the transmission of primary energy to the amplifiers and the resonance caused by the capacity and self-induction of the inductive winding can be avoided.

20 A further object resides in the provision of means whereby sound vibrations can be directly transmitted to the input circuit of an amplifier system whereby corresponding oscillations therein are produced in a new and improved manner.

30 A still further object resides in the provision of means whereby the sensibility of the mechanism for transmitting sound waves to the input circuit of the amplifier can be greatly increased.

Another object resides in the provision 35 of means whereby transmitting circuits for average frequencies can be made without it being necessary to have special apparatus for operating the same.

40 A further object resides in the provision of means whereby the tuning of the circuits can be made in a very exact manner, while the electrical characteristics of the thermionic discharge devices do not influence the tuning.

45 The invention is illustrated in the drawings, of which—

Figure 1 represents a circuit in which sound waves are transmitted to the input circuit of the amplifier;

50 Figure 2 represents the condenser used; and

Figure 3 represents a transmitting circuit involving the use of a plurality of amplifiers.

55 These new circuit arrangements are adapted to increase the amplifying power

of thermionic discharge devices with direct electron current without it being necessary to alter the form, location or normal characteristics of the electrodes. This is made possible by the invention, since the vibrations in the input circuit are caused by a condenser the capacity of which may be changed by the primary energy applied to the input circuit. For instance, one of the plates of the condenser may be movably adjusted so that it is moved by the vibrations of the primary energy.

In Figure 1 is shown a working example of the new circuit arrangement schematically. In this arrangement 1 is an amplifier with three electrodes, the cathode 2, the grid 3 and the anode 4; and 5, 6 and 7 respectively are the corresponding working batteries. Battery 6 is required to place a normal potential on the grid 3. The input circuit also contains a non-inductive resistance 8, and a condenser 9. The condenser 9 comprises a movable condenser transmitting plate 13 and a stationary plate 17. The movable plate 13 is carried by a membrane 14.

The distance between the stationary and movable plates of the condenser 9 can also be regulated according to the strength of the primary energy.

When this circuit arrangement is to be used for sending conversations or sound vibrations which may be recorded on a roll or strip in a well known manner, the movable condenser transmitting plate, represented by the numeral 13, is connected to a membrane such as 14, which membrane in turn is connected to any suitable needle 15 which is caused to vibrate by the sound lines on the plate or roll 16. The cathode battery 5 and the anode battery 7 are used to hold the condenser 9 in the required high tension.

Figure 3 shows a circuit with two amplifiers connected to the roll or record 16 on which speech is recorded in the ordinary way. The needle 15 rests on this record and when the record is turned transmits its movement to the membrane 14, shown particularly in Figure 2. The side of the membrane 14 adjacent the stationary plate 17 of the condenser is provided with a thin metal sheet 13, as above mentioned, so that these two metal plates form a condenser, the capacity of which is changed according to the vibration of the membrane 14. The

condenser in this circuit is represented as connected with a cathode battery 19, a grid battery 20, and an anode battery 21. A resistance 22 is also provided. These connections are such that the condenser receives the total tension of the batteries 21 and 19. If the record 16 is turned the needle will cause the membrane 14 to vibrate and will alter thereby the capacity of 10 the condenser 23. The alternations caused in the condenser cause changes in the input circuit of the tube and influence the potential of the grid 24 whereby the output circuit of the tube is influenced in the well 15 known manner and influences a receiver 25 connected to the anode of the second amplifier 26.

To increase the sound vibrations, a second amplifier 26 can be used in such a circuit 20 as is represented in Figure 3. In the anode circuit of the first amplifier 27 a resistance 28 is placed to the ends of which the input circuit of the second amplifier 26, including a condenser 29, is connected. The changes 25 caused by the output current of vibrations of the first amplifier on the resistance 28 are transmitted therethrough to the input circuit of the second amplifier and produce 30 the desired vibrations in the output circuit of the second tube.

The gradual increase of amplification by the use of a plurality of tubes tapped across resistances in the circuit of previous tubes is known in the art. However, their use 35 in connection with a condenser such as shown in this application is new, as hereby it has been made possible to amplify sound waves in the desired manner with current

amplifiers without the use of transmission coils or spools. With such recorders of 40 sound waves as are now in use by means of a microphone it is necessary to have for each amplifying circuit at least one induction or transmission winding or spool. These windings cause in their amplifying 45 circuit by their self-induction and capacity a resonance which is very often disturbing in the receiver. The arrangements as described, to transform the recorded words into an electrical current, has also the advantage that the arrangement now in use to 50 adjust the vibrating membrane can be preserved and that the movements of the membrane caused by the turning of the record or the roll do not produce any sound, which 55 is always the case with microphones filled with carbon particles.

It is apparent that modifications can be made in the circuit arrangements and in the apparatus used therewith without departing from the spirit of the invention.

What I claim is:

In an apparatus of the character described, a combined diaphragm and condenser plate, a second condenser plate arranged in operative relation to the diaphragm, an amplifying electron tube having a source of electromotive force between its anode and cathode and a source of electromotive force for its cathode, and connections 65 whereby the diaphragm and second condenser plate may be subjected to the combined electromotive force between the anode and cathode and electromotive force for said cathode.

EUGEN REISZ.
